UNITED STATES PATENT OFFICE.

JAMES REILLY, OF BROOKLYN, ASSIGNOR TO THOMAS E. SLOAN, OF NEW YORK, N. Y.

SAFETY-HATCH FOR RAILWAY-CARS.

SPECIFICATION forming part of Letters Patent No. 249,796, dated November 22, 1881.

Application filed October 14, 1881. (No model.)

To all whom it may concern:

Be it known that I, JAMES REILLY, a citizen of the United States, residing in the city of Brooklyn, county of Kings, and State of New York, have invented a new and useful Improvement in Safety-Hatches for Railway-Car Bodies, of which the following is a specification, reference being had to the accompanying drawings, which are made a part thereof.

10 It is necessary for a safety-hatch that it be removable without manipulation in the event of a railway disaster, and it is also necessary, when attached to express or other treasure-bearing cars, that it be securely held in place, 15 when the car is in its proper position on the track, to prevent the operations of robbers through it.

My invention consists in applying an automatic locking-bar to a safety-hatch, which will 20 secure the hatch in place while the car is in an upright position and automatically unlock when the car is turned on its side, permitting the hatch to fall from its place by its own gravity, thus leaving the hatchway clear for 25 the egress of the occupants of the car.

In the drawings, Figure 1 represents a vertical section of a hatch and frame with my locking-bar attached on the line 1 2, Fig. 2. Fig. 2 is a top view of the same. Fig. 3 is a 30 side view of a portion thereof, showing the end of the bar in place when locked; and Fig. 4, the locking-bar.

Similar letters refer to similar parts in all the several figures.

35 A represents a frame or seat to be fixed in the opening in the car, on which the hatch or cover rests. The frame A is made in the form of a metallic hoop or band, *a*, of the diameter required to fit the opening in the car, provided 40 with an annular flange, *a*², on its outer surface, and near the center thereof, through which, by means of screws or bolts, the frame is secured in said opening. The hoop *a* has in opposite sides, immediately below the flange *a*², slots *b*, 45 of sufficient length to permit the locking-bar G to turn on its axis to pass out in either direction in the process of unlocking. In the top of the slots *b* are cut semicircular recesses *b*², in which the locking-bar G is held while in

place. Studs *c*² are inserted in the hoop *a*, on 50 its opposite sides, at line 1 2, Fig. 2, projecting inward to fit the grooves *c* in flange *d*, by which the hatch is guided to its proper place on the seat or frame and retained there. It is obvious that the positions of the grooves and 55 studs can be reversed and the effect remain the same.

D is the hatch or cover, and is represented in the drawings as a bezel for the reception of a glass; but it may be made of a disk of metal 60 or other material. The hatch or cover D is provided with an annular flange, *d*, which fits the inner surface of the hoop *a*. The flange *d* has perpendicular grooves *c* on its opposite sides, at the line 1 2, Fig. 2, to receive studs 65 *c*² when the cover is in place, as above described. On the inner surface of the flange *d*, on opposite sides, at the line 1 2, Fig. 2, are substantial shoulders *E*, projecting inward, to support, by means of a strong screw-stud, F, 70 the locking-bars G. The locking-bars G are constructed in the form of levers, the screw-stud F forming the fulcrum thereof, and securing them to the shoulders *E*. An oblong slot, *g*, through the bars G, near the small end, admits the screw-stud F loosely. The long arm 75 of the lever is enlarged, and by its weight, acting on the short arm through the stud-fulcrum F, the automatic action is obtained.

When the hatch is in a horizontal position 80 and the locking-bars in place the large head of the screw-stud F forms a fulcrum, by means of which the weight of the long arms of the locking-bars G hold the short arms securely fixed in the recesses *b*². When the hatch is 85 projected from a horizontal position the levers cease to exert force in the direction of the recesses, and the short arms are released therefrom, and are carried by the gravity of the long arms free and clear from the slots, thus 90 freeing the hatch or cover, which will then fall by its own weight.

I do not confine myself to the particular construction in all its details of a safety hatch and seat as hereinbefore described. 95

What I claim as my invention, and desire to secure by Letters Patent, is—

1. The combination, in a safety-hatch and

frame for railway-cars, of the cover D, provided with grooves *c* and hoop having studs *c*², substantially as shown and described.

2. The combination, in a safety-hatch and frame for railway-cars, of the automatic locking-bars G, the screw-stud F, and hoop having slots *b* and recesses *b*², substantially as shown and described.

3. The combination, in a safety-hatch and

frame for railway-cars, of the hoop having 10 grooves *c* and the studs *c*², the automatic locking-bar G, the screw-stud F, slots *b*, and recesses *b*², substantially as shown and described

JAMES REILLY.
